UNITED STATES PATENT OFFICE

HENRY G. LYKKEN, OF MINNEAPOLIS, MINNESOTA

PULVERIZED-MATERIAL SEGREGATOR

Application filed October 4, 1924. Serial No. 741,532.

The present invention relates to devices for segregating and collecting ground material into different grades of fineness.

Among the objects of the invention are to 5 provide a novel segregator adapted for use with material grinding and pulverizing devices, such as are disclosed in my co-pending applications Serial No. 658,134, filed August 18, 1923, Serial No. 694,460, filed 10 February 23, 1924, Serial No. 719,468, filed June 12, 1924, and Serial No. 732,436, filed August 16, 1924, patented August 14, 1928, Patent No. 1,680,894; to provide for projecting, preferably centrifugally by a rotor, the 15 material into a series of chambers, preferably surrounding the rotor and arranged to receive the projected material in successive or progressive grades of fineness, the coarser segregated material being preferably 20 returned to the pulverizing or grinding device for further reduction with the other material undergoing action in the grinding or pulverizing device; to provide certain chambers, preferably a number of them, in 25 increasing diameters from the inlet end of the rotor, the remainder of the chambers being preferably of substantially equal diameters; to provide each of the chambers with a collecting pocket to which may be connected 30 a discharged duct or conduit with or without control valves; to preferably provide the ducts with valves, preferably of the butterfly type and preferably connected to a common shaft which may be operated to effect 35 an operation of the valves in unison, but it is to be understood that these valves may be independently operated if desired; to provide for the passage of the material projected in the chambers, to the pockets, preferably 40 substantially tangentially to the chamber, a wall or baffle being preferably interposed between each chamber and pocket and to one side of the path of movement of the material from the chamber to the pocket; 45 to provide a rotor with a preferably axial passage with an inlet at one end for the entry of the material and means for supplying the material to the inlet, the material being preferably in the form of suspended particles carried by a stream of air or the like,

and an outlet at the other end of the rotor passage for the exit of air or the like substantially or wholly free of any suspended particles of material, and with means for conducting off such air or the like and drawing the same from the passage of the rotor; to provide a unit rotor and blower, the impelling members of both being preferably common or integral, also having a common shaft if desired, the blower acting to withdraw the air or the like from the rotor and aiding in the drawing of the material with the air or the like into the passage of the rotor; and to provide for such other objects, capabilities, and advantages as will later more fully appear and are inherently possessed by the invention.

In the drawings illustrating an embodiment of the invention Fig. 1 is a longitudinal sectional view through a segregator constructed in accordance with the invention; Fig. 2 is a transverse sectional view taken on a plane represented by a line 2—2 on Fig. 1 of the drawings; and, Fig. 3 is a transverse sectional view taken on a plane represented by the line 3—3 on Fig. 1 of the drawings.

Referring more particularly to the drawings the embodiment chosen to illustrate the invention comprises a shaft 1 supported in suitable bearings 2 and 3 and provided with a driving pulley 4 at one end of the shaft and with a driven pulley 5 at the other end of the shaft over which may run a belt 6 to a pulley 7 connected to a shaft 8 rotatably supported in bearings 9 and 10. To the shaft 1 are connected or secured any suitable number of hubs 11 provided with radial arms 12 and 13 to the outer ends of which are secured impelling members 14 and 15, these members being preferably formed together as units or integrally as clearly shown in Fig. 1 of the drawings. It will be noted that there is provided an axial passage about the shaft 1 and between the arms 12 and 13 from one end to the other end of the device as clearly shown in Fig. 1 of the drawings. Between the impelling members 14 and 15 are provided a number of radially extending passages through which the material may be centrifugally projected when the rotor is rotated.

Surrounding the rotor are provided a number of chambers 16, 17, 18, 19, 20, 21, 22, 23, 24, 25, 26, 27 and 28 arranged in a series longitudinally or axially of the rotor and also 5 with a certain number of these chambers, as for example chambers 16 to 23 inclusive, being arranged with progressively increasing diameters from the inlet end of the device, the remaining chambers, as for example chambers 10 23 to 28 inclusive, being substantially of equal diameter. At the inlet end of the device is provided an inlet passage or conduit 29 having an inlet opening 30 leading into the inlet end of the central passage of 15 the rotor. At the other end of the device is provided a chamber 31 in which the impelling members 14 operate or rotate to draw air or the like from the outlet end of the rotor passage and to project the same through a 20 discharge passage 32, this passage leading, if desired, to the grinding or pulverizing device for supplying air or the like into the same for aiding in air separating the fine particles being projected by the rotor of the grinding 25 device, or the same may be lead into the atmosphere. It will be observed that the impelling members 14 are of greater diameter than the impelling members 15 of the rotor so that a suction may be created by the impelling members 14 as well as a rapid exit of the 30 air or the like into the discharge 32.

The pulverized material will be carried by a stream of air or the like in more or less suspended form from the pulverizing device, 35 through the passage 29 into the opening 30 and into the central passage of the rotor where centrifugal action will carry the particles to the chambers 16 to 28 inclusive. The heavier particles will be acted upon first and 40 projected into the chambers 16, 17 and 18 and the less coarse particles will be projected into chambers 19, 20, 21, and 22 and the finest particles will be projected in the remaining chambers 23 to 28 inclusive. The coarser 45 particles may be led back into the grinding device to be acted upon again with the material being reduced therein.

Each chamber has a substantially tangential discharge passage 33 leading into a pocket 50 34 provided at the bottom thereof with a valve 35 having therein a rotating butterfly valve 36 fastened to the shaft 8. To each valve structure 35 may be connected a discharge conduit or duct 37 leading to any desired 55 point for the conveying off of the segregated material collected in the pocket 34 and fed by the valve 36 into the duct 37. Between the chambers and the collecting pocket may be interposed a wall or baffle plate 38 extending 60 part way across the space between the chamber and the pocket and to one side of the passage 33, as clearly shown in Fig. 2 of the drawings.

In the form of device shown, all of the 65 butterfly valves 36 are secured to the common

shaft 8 and the latter rotated so that the butterfly valves will operate in unison and feed the material collected in the pockets 34 into the respective ducts 37 thereof.

Practically all the particles will be cast into these chambers in substantially successive grades of fineness and the air or the like proceeding or drawn from the outlet end of the rotor will be practically free of any particles and discharged by the blower 14 into the discharge passage 32. The finer particles collected in the discharge conduits or ducts 37 of the chambers 23 to 28 inclusive may be conducted to suitable points of use such as in a combustion chamber of a furnace or other places desired.

While I have herein described and upon the drawings shown, one particular form of construction in illustrating the invention, it is to be understood that the invention is not limited to the particular construction, details and arrangement of parts disclosed, but that other constructions, details and arrangements of parts are comprehended by the invention without departing from the spirit thereof. 85 90

Having thus described my invention,

I claim:—

1. A segregator for ground material, comprising a rotor for centrifugally projecting the material, a series of chambers arranged along the length of and surrounding the rotor for receiving the projected material in successive grades of fineness, said rotor having an axial passage, means at the inlet of said passage for entry of the material in suspended state with air or the like, said rotor having means at the outlet of said passage for withdrawing the air or the like substantially free of suspended material.

2. A segregator for ground material, comprising a rotor for centrifugally projecting the material, a series of chambers surrounding the rotor for receiving the projected material in successive grades of fineness, said rotor having an axial passage, means at the inlet of said passage for entry of the material in suspended state with air or the like, said rotor having means at the outlet of said passage for withdrawing the air or the like substantially free of suspended material, a number of said chambers increasing in diameter from the inlet end of said passage and the remainder of said chambers being of substantially equal diameters. 115

3. In a segregator for ground material, a housing, a rotary impeller longitudinally disposed in the housing, the housing having an inlet for the material laden air at one end of the impeller and having a series of collecting pockets arranged along the length of and surrounding the impeller and having an outlet tangent to the impeller at the opposite end of the same. 125 130

4. A segregator for ground material, comprising a housing, a rotor in said housing, means for causing an uninterrupted stream of material laden air to flow through said housing and along said rotor, and a series of chambers in said housing and surrounding said rotor to receive material projected from said stream by said rotor in successive grades of fineness. 70
5. A segregator for ground material, comprising a housing, a rotor in said housing, means for causing an uninterrupted stream of material laden air to flow through said housing and along said rotor, a series of chambers in said housing and surrounding said rotor to receive material projected from said stream by said rotor in successive grades of fineness, and a discharge conduit for each of said chambers. 75
6. A segregator for ground material, comprising a housing, a rotor in said housing, means for causing an uninterrupted stream of material laden air to flow through said housing and along said rotor, a series of chambers in said housing and surrounding said rotor to receive material projected from said stream by said rotor in successive grades of fineness, each chamber having a collecting pocket, and a discharge conduit for each of said pockets. 80
7. A segregator for ground material, comprising a housing, a rotor in said housing, means for causing an uninterrupted stream of material laden air to flow through said housing and along said rotor, a series of chambers in said housing and surrounding said rotor to receive material projected from said stream by said rotor in successive grades of fineness, a control valve for each chamber, and a common shaft for the valves. 85
8. A segregator for ground material, comprising a housing, a rotor in said housing, means for forcing a stream of material laden air through said housing and along said rotor, and a series of chambers arranged along the rotor for receiving material projected from said stream by said rotor in successive grades of fineness, said chambers varying in cross-sectional area from one end of the series to the other end thereof. 90
9. A segregator for reduced material, comprising a series of chambers having communicating openings for providing a free passageway through said series of chambers, means for moving a stream of material laden air along said passageway, and means for rotating said stream in said passageway while said stream is moving along said passageway for causing particles of material in said stream to leave said stream from different parts thereof and to be received in said chambers. 95
10. A segregator for reduced material, comprising a series of chambers having communicating openings for providing a free
- passageway through said series of chambers, means for moving a stream of material laden air along said passageway, means for rotating said stream in said passageway while said stream is moving along said passageway for causing particles of material in said stream to leave said stream from different parts thereof and to be received in said chambers, and means for varying the rate of movement of said stream along said passageway for governing the distribution of the particles received in said chambers. 100
11. A segregator for ground material, comprising a housing, an impeller mounted in the housing for centrifugally projecting the material, the housing having formed therein a series of chambers arranged along the length of and surrounding the impeller for receiving the projected material in successive grades of fineness, an inlet at one end of the impeller housing for supplying material laden air to the impeller, the housing having an outlet at the opposite end of the impeller and related thereto so that the impeller also serves as an exhaust fan for drawing the air through the housing. 105
12. A segregator for ground material, comprising a rotor for centrifugally projecting the material, means for drawing air laden with the material longitudinally into the rotor, and a plurality of chambers arranged in a series along the length of and around the rotor for receiving the projected material in successive grades of fineness, each of said chambers having substantially tangential discharge outlet for the material projected thereinto. 110
13. A segregator for ground material, comprising a rotor, means for drawing material laden air longitudinally through the rotor, and a series of chambers arranged along the length of and surrounding the rotor for receiving the projected material in successive grades of fineness, each chamber having a depending pocket, and a wall extending part way across the passage from the chamber to the pocket. 115
- In witness whereof, I hereunto subscribe my name to this specification.
